UNITED STATES PATENT OFFICE.

EMMIT G. LATTA, OF SYRACUSE, NEW YORK.

TYPE-WRITING MACHINE.

1,173,589.

Specification of Letters Patent. Patented Feb. 29, 1916.

Application filed April 12, 1912. Serial No. 690,355.

To all whom it may concern:

Be it known that I, EMMIT G. LATTA, a citizen of the United States, residing at Syracuse, in the county of Onondaga and State of New York, have invented a new and useful Improvement in Type-Writing Machines, of which the following is a specification.

This invention relates to improvements in visible writing typewriting machines in which the type-bars are pivotally mounted so as to make the impressions at the front side of the platen.

The improvements are especially applicable to machines in which the type-bars are adapted to be shifted for placing one or another of the different sets of type carried thereby in printing relation to the platen, but the invention is not necessarily restricted to such machines.

The objects of this invention are to construct and arrange the type-bar hangers in a novel way which enables them to be more readily assembled and adjusted for alining the type; also to provide ball bearings for the type-bars which are of an improved construction especially adapted to the novel arrangement of the type-bar hangers; and also to improve typewriting machines in the several respects hereinafter described and set forth in the claims.

In the accompanying drawings, consisting of three sheets: Figure 1 is a fragmentary longitudinal sectional elevation of a typewriting machine embodying the invention. Fig. 2 is an enlarged section of one of the type-bar hangers. Fig. 3 is an end view of the adjustable bearing cone detached. Fig. 4 is an end view of the bearing adjusting plate. Figs. 5 and 6 are elevations of two of the hangers detached. Fig. 7 is a front elevation of the operating parts of the machine. Fig. 8 is a plan view, partly in section, of the ribbon vibrating and universal bar mechanism. Fig. 9 is a fragmentary sectional elevation of the vibrating mechanism in line 9-9, Fig. 8. Fig. 10 is a front elevation, partly in section, of a modified hanger arrangement. Fig. 11 is a sectional elevation of one of the hangers shown in Fig. 10 and the type-bar connected thereto. Fig. 12 is an elevation of one of the space plates used in the modified construction. Fig. 13 is a fragmentary sec-

tional elevation of a ribbon vibrating mechanism of modified construction. Fig. 14 is a front elevation partly in section thereof.

Like reference characters refer to like parts in the several figures.

A represents the main frame of the machine, having a top plate *a*; B the platen carriage which supports the platen C; D the carriage escapement; E one of the type-bars, which are pivoted in an arc below the platen, so as to swing upwardly and rearwardly to make the impression at the front side of the platen; F one of the levers which are operated by the finger keys and connected by links *f* to the type-bars for actuating them. This invention is not concerned with these parts, and they may be of any suitable construction. They are illustrated to show their relation and co-action with the other parts of the machine.

The top plate *a* shown, which is preferably removably secured on the upright sides of the frame in any suitable manner, has an open middle portion spanned by a bridge *a'* which supports a ball-bearing carriage track or guide *a''*. The front portion of the top plate is provided at opposite sides with inclined seats *a''* on which the ribbon spools (not shown) are arranged in an inclined position so as to deliver the ribbon in line with the ribbon vibrator;

The carriage escapement D may be of any suitable construction but it is preferably mounted as shown, on a bearing *d* on the rear central portion of the bridge *a'*, and the shaft of the escapement wheel *d'* is provided as usual at its front end with a pinion *d''* which meshes with a rack bar on the carriage.

d'' is the movable lever or part controlling the action of the escapement wheel.

G represents a support or plate on which the bearing hangers for the type-bars are mounted. Each of the type-bars is provided with two type and the hanger support or plate G is preferably mounted so that it can be shifted for placing one or another of the two sets of type in the printing relation with the platen.

In the construction shown in Figs. 1-9, the hanger support G is pivoted to the front ends of two pairs of arms *g* *g'* which are connected respectively to rock shafts *g''* *g'''* mounted in suitable bearings on the opp-

site sides of the main frame. The hanger support G can be shifted by any suitable means, such, for instance, as a cam lever g^4 adapted to be rocked by a shifting key g^5 and acting on a roller or part g^6 suitably attached to the support. The support or plate G is preferably stamped from stock of suitable thickness and has rearwardly bent pivot lugs g^7 by which it is pivoted to the supporting arms. g^8 indicates openings in the ends of the plate G in which are secured supporting rods, not shown, for the type-rest. The plate G is preferably grooved on its rear side to receive the heads of securing screws h for the type-bar hangers H H' H² H³. The groove for the securing screws for the central hangers is shown at h' , Fig. 1, and the grooves for the screws of the remaining hangers are indicated by dotted lines in said figure. The plate is thus grooved to reduce its thickness, so that the whole series of oblong holes h^2 , through which the securing screws for the hangers pass, may be punched at one operation. The holes for two extra outside hangers are shown at h^3 , Fig. 7, these hangers being omitted. The other holes are of similar shape. The front face of the plate G is plain or flat. The grooves h' for the screw heads and the slots through which the screws pass are large enough to permit a limited vertical movement of the screws therein, sufficient for alining the type.

In the construction shown in Figs. 1-9, the hangers H H' H² and H³ have bodies or attaching portions which are secured in upright position, parallel with each other, on the supporting plate G, and bearing ends which are bent at the necessary inclinations to the body portions to permit the type-bars to swing in radial planes and make the impressions at a common point on the platen. The bodies of all of the hangers are of uniform thickness sufficient to provide the required space between the type-bars when the hangers are secured face to face on the support, and by making their bearing ends of appropriate lengths to locate the bearings in an arc, as shown, the required spaces between the bearing ends are secured, such spaces increasing in width from the center toward the ends of the series. This increasing space is required to accommodate the increasing offset or inclination given to the heads of the type-bars to enable them to nest properly in the type-bar basket. The hangers may be formed from stock which is rolled in two different thicknesses, suitable for the body and bearing portions of the hangers, or the bearing ends may be reduced in thickness by swaging or machining. The hangers are arranged in a central group and two side groups at each end of the central group, and are clamped together by screws i i' i^2 i^3 , as presently explained. The hangers are made in pairs, or rights and lefts, and with bodies of two different forms, as shown in Figs. 5 and 6. The hangers H' have screw-threaded holes h^1 (see Fig. 6) in their bodies; the hangers H² have similar threaded holes at their lower ends, and the end hangers H³ of the several groups against which the heads of the clamping screws bear, have smooth holes slightly smaller than the screw heads through which the screws pass. The remaining hangers H all have two open-ended slots h^4 , as shown in Fig. 5, for the passage of the clamping screws. The clamping screws are of four different lengths. The screws i and i' extend through the hangers of the two side groups at each end of the series and have threaded ends screwed into the threaded holes in the hangers H'. The screw i^2 passes through the center and adjacent side groups and has a threaded end screwed into the threaded hole in the hanger H² of one side group, and the other screw i^3 passes through the hangers of the central group and is similarly screwed into the hanger H² at the end of this group. The securing screws h are screwed into holes in the rear edges of the hangers, the holes being staggered to make room for the screw heads, as indicated by the dotted lines in Fig. 7.

In assembling the hangers, after the type-bars have been pivotally secured thereto and the operating links connected to the type-bars, the hangers are secured loosely on the supporting plate G by the screws h , after which the plate G is pivotally connected to its supporting arms and the operating links connected to the upper ends of the actuating levers. The clamping screws i — i^3 are not screwed in tightly until after the type-bars are alined, but they are screwed in far enough to create sufficient friction between the hangers to hold them against accidental movement while being alined. As fast as the several bars are alined the hangers therefore are locked to the plate G by the screws h , and when all of the type-bars have been properly alined the several clamping screws i — i^3 are screwed in with sufficient force to rigidly clamp the whole series of hangers together, thus making a more rigid and reliable connection of the hangers to the support than is possible with hangers independently secured within the same space. Any one of the hangers H having the open slots can be detached whenever this may be necessary, by first removing its securing screw h and loosening the two clamping screws which pass through that hanger, disconnecting its link from the auxiliary lever and pulling the hanger straight outwardly to the front. In the case of the hangers H' and H² having the threaded holes for the clamping screws, it is necessary to remove

- the clamping screws also. In any case, any desired hangers can be detached and replaced without disturbing the others. A convenient way to assemble the hangers is to first loosely clamp together by the screws i^3 the hangers of the central group, then loosely clamp together the nine hangers of each of the two side groups by the two short screws i^3 . The five groups are then placed together and loosely clamped by the screw i^2 . This is all done before securing the grouped hangers on the supporting plate G. The hangers constructed and arranged in this manner may cost slightly more to produce than some forms of hangers now in use, which are arranged in radial lines on their support, but the support G is less expensive than one made for radially arranged hangers, so that the total cost is about the same.
- But an absolutely rigid support for the type-bars is produced and the hangers cannot become loose by reason of side strains caused by collisions between the type-bars, and so much time is saved in alining the type that the described construction is in reality much less costly than other constructions of comparative value. The great advantage gained in alining the type will be readily appreciated when it is understood that any of the type may be raised or lowered vertically at right angles to the printing line without affecting the lateral position of the type at the printing point, by simply adjusting the hangers vertically up or down. The whole series of type-bars can be properly alined with the same ease and speed that is ordinarily required to aline the central bar in machines having radial hangers. Thus not only is there an important saving in time of the most expensive labor required in the manufacture of type writers, but the work can be performed with labor of less skill and consequently more economically.
- Ball bearings of the usual forms are not suitable for pivoting the type-bars to the hangers, since the hangers arranged in parallel planes within the small space shown do not afford sufficient room. Therefore, having especial reference to the described construction of the hangers, the bearings are preferably constructed as follows: The bearing end of each hanger is machined to form a low cone frustum K on one side thereof and is provided with a relatively large central hole k. The opposite side of the hanger is counterbored and screwthreaded, as shown at k', Fig. 2, to receive a screwthreaded adjusting plate k² for an adjustable cone k³ which is secured to the plate k² by a central screw k⁴ having a head located in a counterbore in the adjusting plate k². The adjustable cone k³ has a projecting shank which enters the hole k; the hole and shank being circular with flat sides, or of other shape adapted to prevent the cone from turning in the hole. The inner end of each type-bar is made with an internal annular ball race or groove and a circular row of balls k⁵ is confined between this race and the two cones K and k³. After assembling the parts of the bearing, the adjustable cone is drawn in by the screw k⁴ until the flat end of the extension of the adjustable cone bears against the inner face of the adjusting plate k². The adjusting plate is then unscrewed until, acting through the screw k⁴, it has drawn the cone k³ into proper relation to the balls, or until the adjustable cone acting with the fixed cone has forced the balls into the race in the type-bar so as to prevent looseness. Then the parts are locked by screwing in the locking screw k⁶ with considerable force.
- Should the bearing be stiff it is only necessary to unlock it and screw in the adjusting plate k² slightly and again lock it as before. As the shank of the adjustable cone is held from turning in the fixed cone it is evident that the adjusting plate is held against turning in its seat when the locking screw k⁶ is screwed in tightly. The adjusting plate k² is made with slots k⁷ or is otherwise formed for the engagement of a tool for turning it, and it is also preferably split as shown, and slightly expanded so that it has to be compressed somewhat to screw it into place. This causes sufficient friction to prevent accidental movement of the plate when it is unlocked. This bearing is easy to readjust to take up wear after use, by unlocking the screw k⁶, very slightly unscrewing the adjusting plate k² and relocking, as before.
- As the meeting plane ends of the adjusting plate and adjustable cone bear flat against each other in a plane perpendicular to the axis of the bearing, the adjustable cone must be held at all times parallel with the fixed cone, assuming of course that the adjusting plate k² is properly fitted in the hanger, and it will be apparent that, owing to the relatively large diameter of the adjusting plate any slight misfit in this part will be much less serious than if a smaller screw-threaded part was depended on to hold the cones parallel. It has been found extremely difficult to make small ball bearings of this nature that depend on screw-threaded parts to hold one cone concentric with the other, with sufficient accuracy on a commercial scale.
- In the above construction both the adjusting plate k² and the lock screw k⁶ may be eccentric to the cones without objection in this respect. Greater dependence could be placed on accurate fitting of the cone extension in the hanger, and exact central location of the hole to receive it, than to screw the cone extension into the fixed cone as has

been done by others. Preferably, however, the cone extension is fitted loosely in the fixed cone, as shown, and the balls are relied upon to force the adjustable cone into proper concentric relation to the fixed cone when adjusting the bearing. The balls naturally do this if a little care is used in making the adjustment, and, when locked, the adjustable cone will retain its position. In either case the trouble caused by a loose or eccentric locking screw is overcome, as the only function of the screw k^4 is to rigidly lock the adjustable cone to the adjusting plate.

If machining the hangers to form the fixed bearing cones K, a small flange or dust guard k^7 is preferably left on the upper end of the hanger which overhangs the space between the hanger and the type-bar at the upper rear portion of the bearing. The universal bar hereinafter described extends over these guards on the several hangers, so that the guards prevent any dust that may fall behind the universal bar from entering the bearings.

L represents a curved universal bar which is substantially parallel with the arc of the type-bar bearings and is supported over the bearings in position to be struck by the type-bars as they approach the platen, preferably in the following manner: M represents a bar which is secured, for instance, by screws m to lugs m' on the upper central part of the plate G and is provided at its ends with cross arms m^2 . In the front and rear ends of these arms, parallel rock shafts m^3 m^4 are journaled which are provided with rigid depending arms m^5 . The universal bar has fixed thereto rearwardly extending arms m^6 which are pivoted to the said depending rock arms m^5 . The universal bar is thus hung so that it is adapted to be moved rearwardly when struck by any one of the type-bars. A suitable spring m^7 acts to restore the universal bar to its forward or normal position. The spring shown is connected at opposite ends to an arm m^8 on the rock shaft m^3 and to an arm m^9 on one leg of the center guide for the type-bars hereinafter described.

The universal bar is connected to the carriage escapement for actuating it, preferably as follows: N represents a nearly horizontal link pivoted at its front end to the rock arm m^8 and at its rear end to the depending arm of a bell crank lever n which has a rearwardly extending arm connected by a rod n' to the controlling lever d^3 of the carriage escapement. The bell crank lever n is pivoted on a bracket n^2 secured to the supporting bridge for the carriage track. As the carriage escapement is mounted on a fixed part of the machine while the universal bar is mounted on the shifting supporting plate G, the link N is pivoted to the bell crank n in a plane midway between the normal and shifted positions of the pivot which connects the link to the arm m^8 , so that the action of the escapement will be the same in both positions of the supporting plate G. By these connections the escapement wheel is released every time the universal bar is moved rearwardly by a type-bar, and the spring m^7 acts to restore the escapement lever as well as the universal bar to the normal position.

O represents the vibrating ribbon guide or vibrator, which may be constructed and mounted in any suitable way. The vibrator shown has ears o by which it is slidably retained on a stationary center guide P for the type-bars, and it is pivoted at its lower end to the front end of a vibrator lever Q. The center guide shown has downwardly and rearwardly extending legs p rigidly secured to the bar M, preferably by the securing screws for this bar. The center guide slides up or down in front of the vibrator when the type-bars are shifted to different printing relations to the platen and always retains a fixed position relative to the type-bars. The vibrator O is also actuated by the universal bar through mechanism, which, as shown in Figs. 1-9, is constructed as follows: r and r' represent two arms of different lengths which project from a hub R loosely sleeved on the central part of the rock shaft m^3 . A nut r^2 screwed on the shaft m^3 and bearing against the hub of the arms r r' retains a tapered stud r^3 on the rock arm m^8 in a hole in the arm r , whereby the arms r r' are locked to the rock shaft m^3 so that they will be rocked when the universal bar is actuated. When it is desired to silence the vibrator, the nut r^2 is unscrewed, when a spring r^4 between the arms m^8 and r will disengage the latter arm from the stud r^3 . The arms r r' can be relocked to the rock shaft by again screwing up the nut r^2 .

S represents a link arranged with its front end between the arms r r' and extending rearwardly therefrom with its rear end between correspondingly spaced arms s s' of different lengths depending from the ribbon vibrating lever Q, which is pivoted on the bracket n^2 . The arms r r' are provided with inwardly extending round-ended pins s^2 s^3 adapted to enter registering holes in the front end of the link S, and the arms s s' have similarly arranged pins s^4 s^5 adapted to enter registering holes in the rear end of the link S. In the position of the link shown in the drawings it engages the pins of the short arm r' and long arm r and connects these arms. By moving the link sidewise it is disengaged from the pins s^3 s^5 and is engaged with the other pins s^2 s^4 , thereby connecting the long arm r to the short arm s . Thus by shifting the link S sidewise one way or the other, the vibrator

lever can be given a short or a long throw suitable for using either of two different ink fields on the ribbon. The pins s^2 — s^3 are of such length that the link does not leave one pair of pins until the other pair has partly entered the holes in the link, thus insuring the ready shifting of the link. When however, the link is in operative connection with one pair of arms, the other pair is left perfectly free. The link is shifted sidewise for changing the throw of the vibrator by a plate s^6 provided with upwardly extending arms having slots s^7 in which the link S is held from sidewise movement but is permitted to reciprocate freely lengthwise. The shifting plate is slidably secured on the bar M , for example, by a screw s^8 , Fig. 8, passing through a slot in the plate, and has an extension s^9 ending in an upturned finger piece located in a convenient position for moving the shifting plate to shift the link S . The extension s^9 is provided with a tooth or projection on its lower side adapted to snap into either one of two notches s^{10} , Fig. 8, in the bar M for holding the plate with the link in engagement with either pair of arms. Any other suitable shifting means for the link S can be used.

The pins for the link S are located so that when the type-bars are shifted the operative pin at the front end of the link will be moved from a position below the plane of the operative pin at the rear end of the link to a corresponding distance above that plane, and thus produce like movements of the ribbon in both positions of the type-bars.

As seen in Fig. 1, the vibrator lever Q is curved downwardly and the track supporting bridge is recessed above the lever to enable the lever to move the desired distance in the limited room available. The link S is also curved downwardly so as not to interfere with the lever Q when the parts are shifted for upper case work.

Figs. 10-12 show a modified construction in which the hangers are also arranged closely together in parallel planes in such a way that any one of the hangers can be detached without disturbing the others.

The hangers T are made of blanks of uniform thickness throughout their length, sufficient for the fixed cones of the type-bar bearings, which are constructed as before described, to be machined thereon. The hangers are spaced by sheet metal plates t of uniform thickness, and all but the two plates at the ends of the series are of the same dimensions. In assembling, long screws t' and t'' are passed through a bracket t^3 and the whole series of plates t and nuts t^4 and screwed into a bracket t^5 , and jam nuts t^6 are screwed on the plates to lock them to the bracket. Then the hanger at the right of the series is placed in position by

passing the two slots t^7 thereof, shown in Fig. 11, over the screws t' and t'' from the rear, after which the point of a long screw t^8 is passed through the bracket t^5 and the hanger to hold the hanger in place. The other hangers are applied and secured in the same way, and then the nuts t^6 are turned up enough to clamp the whole series of hangers against accidental movement while being aligned. After all of the hangers are aligned the nuts are screwed up hard enough to rigidly lock the hangers all together. The screw t^8 is threaded only a short distance from its head, leaving the part that enters the hangers and space plates smooth. The holes in the space plates t fit the screw t^8 , while the holes in the hangers are large enough to permit the hangers to be adjusted up or down a short distance as may be required in alining the type. Any one of the hangers may be detached without disturbing the others, by inserting a spring spacing tool into the openings in the front of the hanger that is to be detached. This acts to hold the adjacent space plates in position and create friction enough to hold the hangers from accidental movement after the nuts t^6 are loosened slightly to permit the hanger to be slipped out rearwardly.

Fig. 10 shows one-half of the hangers and their space plates in position, with one of the type-bars mounted on its hanger. The other half of the space plates are shown without hangers. This construction of the hangers and support for the same is intended more especially for a machine with a shifting carriage but it may be easily arranged as in the first construction to shift the type-bars, if so desired. It has the described advantages of the first construction in alining the type.

Figs. 13 and 14 show a ribbon vibrating mechanism which is interchangeable with the vibrating mechanism first described. The universal bar and its supporting shafts m^3 and m^4 are the same as described, and the vibrator lever Q and escapement connections are also the same, but instead of the connected arms r and r' used in the first construction, arms U , U' are used which are independently mounted on the shaft m^3 and are spaced by being seated in slots in a sleeve u which is pinned or otherwise secured to the shaft. The arm u' for the restoring spring m^7 and the link N are made integral with the sleeve u . Two separate links u^2 and u^3 take the place of the single double acting link P first described, and they are permanently pivoted to the arms U and U' at their front ends, and to the arms q and q' of the vibrator lever at their rear ends. Two short sleeves v and v' are mounted to slide on the shaft m^3 outside of the sleeve u . Pins v^1 and v^2 project inwardly from these sleeves, and each sleeve has a flat spring v^4

rigidly secured to its lower side. These springs contact at their ends and each spring has a tooth or projection to snap into the notches along the underside of the sleeve u .
 5 The sleeve u has a hole for the pins v^2 v^3 extending throughout its length, parallel with the shaft m^3 , and pin holes in the arms U U' register with the pins when the parts are in normal position. As seen in Fig. 14, 10 the pin v^2 is in place to lock the arm U' to the shaft m^3 and vibrate the upper field of the ribbon to and from the printing point. To vibrate the lower field it is only necessary to push in the sleeve v as far as it will 15 go, which, owing to the contacting ends of the springs v^4 , pushes the other sleeve v' out of locking position and releases the arm U' at the same time that the arm U is locked to the shaft m^3 . In order to silence the 20 vibrator it is only necessary to withdraw the locking pin from whichever arm may be in use, without pushing in the other locking pin. Both arms U and U' with the links u^2 u^3 vibrate together at all times when 25 either arm is locked to the shaft m^3 , and whichever arm is locked controls the movement of the other arm through the arms q q' and the idle link. The pivots at the ends of the links u^2 and u^3 are located in the 30 same positions as the four pins that connect the link S with the arms r r' and s s' in the first construction, and the same result is accomplished in both cases.

I claim as my invention:

- 35 1. In a typewriting machine, the combination of a series of radially arranged type-bars, and a series of adjustable parallel bearing hangers pivotally supporting the type-bars, substantially as set forth.
- 40 2. In a typewriting machine, the combination of a series of radially arranged type-bars, and a series of parallel bearing hangers supporting the type-bars, said hangers being independently adjustable in the direction of their length, substantially as set forth.
- 45 3. In a typewriting machine, the combination with a traveling platen, and a series of radially arranged type-bars, of bearing hangers to which the type-bars are pivoted arranged in parallel planes perpendicular to the line of travel of the platen, substantially as set forth.
- 50 4. In a typewriting machine, the combination of a series of radially arranged type-bars, a series of parallel hangers supporting the type-bars, and means for clamping the hangers together laterally, substantially as set forth.
- 55 5. In a typewriting machine, the combination of a series of radially arranged type-bars, a series of parallel hangers to which the type-bars are pivoted a common support for the hangers, and means for independently and adjustably connecting the

hangers to said support, substantially as set forth.

6. In a typewriting machine, the combination of a series of radially arranged type-bars, and a series of parallel hangers having 70 integral bearing ends to which the type-bars are pivoted arranged in radial planes corresponding with the type-bars connected thereto, substantially as set forth.

7. In a typewriting machine, the combination of a series of radially arranged type-bars, a series of parallel hangers supporting the type-bars, a common support for the hangers, means for independently securing the hangers to the support, and means for 80 clamping the hangers laterally together, substantially as set forth.

8. In a typewriting machine, the combination of a series of radially arranged type-bars, a series of parallel hangers supporting 85 the type-bars, a common support for the hangers, means for connecting the hangers together independently of said support, and means for connecting the hangers individually to said support, substantially as set 90 forth.

9. In a typewriting machine, the combination of a series of radially arranged type-bars, a series of adjustable parallel hangers to which the type-bars are pivoted arranged 95 side by side, said hangers being of suitable thickness to properly space the type-bars, and means for supporting the hangers, substantially as set forth.

10. In a typewriting machine, the combination of a series of radially arranged type-bars, a series of parallel type-bar hangers, and means passing through the hangers for clamping them together, substantially as set 100 forth.

11. In a typewriting machine, the combination of a series of radially arranged type-bars, parallel bearing hangers for the type-bars, screws passing through said hangers for clamping them together face to face, a 110 supporting plate, and securing devices separately securing said hangers adjustably to said supporting plate, substantially as set forth.

12. In a typewriting machine, the combination of a series of radially arranged type-bars having annular ball races at their inner ends, and a series of parallel type-bar hangers having radially arranged ball bearings for the type-bars including fixed cones on 120 said hangers, substantially as set forth.

13. In a typewriting machine, the combination of a series of radially arranged type-bars having annular internal ball races at their inner ends, a series of hangers each 125 having a fixed cone with a central opening, an adjusting plate adjustably seated in said fixed cone, an adjustable cone having an extension entering said opening and bearing against the adjusting plate, ball bearings, 130

and a screw for locking said adjustable cone to said adjusting plate, substantially as set forth.

14. In a typewriting machine, the combination of a series of radially arranged type-bars having annular internal ball races at their inner ends, a series of hangers each having a fixed cone with a non-circular central opening, an opposable adjustable cone having a non-circular extension entering said central opening, a screw holding said extension in said opening, means for adjusting said adjustable cone, and balls in said races, substantially as set forth.
15. 15. In a typewriting machine, the combination of a series of radially arranged type-bars having annular internal ball races at their inner ends, a series of hangers each having a fixed cone with a central opening, an adjustable cone having a rigid extension seated in said opening and held against turning therein, means located within the fixed cone for adjusting said adjustable cone axially, and a screw acting to lock said adjusting means and secure the two cones rigidly together, substantially as set forth.
16. In a typewriting machine, the combination

of a series of radially arranged type-bars having annular internal ball races at their inner ends, a series of hangers each having a fixed cone with a central opening, an adjustable cone having an extension which is adapted to slide in said opening and have a limited lateral movement therein, means for adjusting said adjustable cone toward and from the fixed cone and locking said cone extension in different axial positions, and balls in said races, substantially as set forth.

17. In a typewriting machine, the combination of a series of type-bar hangers, a hanger support formed of a flat plate of metal having grooves to reduce the thickness of the plate, and a series of holes for hanger connecting devices punched through grooved portions of said plate, substantially as set forth.

Witness my hand, this 4th day of April, 1912.

EMMIT G. LATTA.
